UNITED STATES PATENT OFFICE.

GEORGE D. BALDWIN, OF HOBOKEN, NEW JERSEY.

ART OF BUILDING RAILROADS.

1,283,621.

Specification of Letters Patent. Patented Nov. 5, 1918.

Application filed December 12, 1917, Serial No. 206,739. Renewed September 13, 1918. Serial No. 253,986.

To all whom it may concern:

Be it known that I, GEORGE D. BALDWIN, a citizen of the United States, and a resident of Hoboken, Hudson county, New Jersey, have invented a new and useful Improvement in the Art of Building Railroads, of which the following is a full, clear, and exact description.

My invention relates to improvements in the art of building railroads, and the principal object of my invention is to build a railroad much cheaper and faster than has been possible with previous systems. My invention is also intended to provide means for laying at one operation a long stretch of permanent track so that when laid the ordinary traffic of the road can be at once operated on the track. Usually a partly completed roadbed is provided, permanent rails are laid to the gage of the ordinary track, and the construction train is run out on these rails, the roadbed built up and finished as fast as possible. This sometimes involves the practical destruction of the rails, as they are warped and twisted by the heavy construction train. Furthermore, the construction train usually has at its forward end a car provided with derricks and conveying apparatus intended to reach out in advance of the car to perhaps the length of the car or a little more, has a gang of men employed to work on this short section of track, after which the train is advanced and the operation repeated. This is the most general way of operation, and the result is that the gang of men employed are in one another's way, and enough men cannot be used to make very rapid progress. My invention is intended to obviate these difficulties and provide means whereby a long stretch of track, say half a mile or more, can be quickly cheaply and permanently laid, and the men employed used to the best possible advantage, which will appear clearly from the description to follow.

Reference is to be had to the accompanying drawings forming a part of this specification, in which similar reference characters indicate corresponding parts in all the views.

Figure 1 is a broken perspective view illustrating a form of apparatus adapted for use in carrying out my method and showing one stage of the operation.

Fig. 2 is a similar view showing a further stage of the operation.

Fig. 3 is a diagrammatic view showing how the construction train can be laid out and

Fig. 4 is a diagrammatic side elevation of the structure shown in Fig. 3.

In carrying out my invention it is assumed that the roadbed has already been laid to grade, and the invention provides for the quick and permanent laying of the track. In this operation the engineers' stakes 10 are first laid out substantially as usual giving the line and grade of the track. A light narrow gage track is then laid out in sections 11, these sections comprising pairs of rails coupled together by ties 12 and provided at their end portions with supports 13, which are laid on ties 14. These are spaced apart at convenient distances, say preferably about 15 feet, and the ties 14 are laid to permanent grade and line in accordance with the indications of the engineers' stakes. A tie 14 can be laid and graded, a section of the track 11 laid thereon, then another tie laid, and another section of track 11 laid and coupled to the first section, and this arrangement can be carried out to the distance intended to be covered by the tracks and rails on the construction train as presently described. It will be readily seen that this arrangement may be extended for an indefinite distance, limited only as above stated, and the construction train can easily carry the materials for laying a half mile track at one operation. As soon as this is done the laying crew is strung out along the distance of track to be laid, preferably about four men to each fifteen foot section, two on each side of the track 11, are provided, then a train of light conveyer cars 24 is run out on the track 11 to the desired limit. The flat cars 15 of the construction train have meanwhile been brought up on the permanent track to the point where the new track is to be laid, and these flat cars 15 are provided with parallel tracks 16 of the same gage as the track 11, and trucks 17 which are loaded with ties 18 have previously been arranged on the construction train as shown in Fig. 3, and the cars 17 can be propelled in any convenient way. To provide for rapid work, however, means should be provided for handling them quickly, and a convenient means is to provide a cable 19.

The trucks 17 can be provided with any suitable form of cable grip, and the flat cars

15 are connected by bridges 20 so that the tracks 16 are continuous along the desired number of these cars. On the forward car 15 switches 21 are provided so that the 5 trucks can be switched to the track 11, and an inclined bridge 23 connects the forward car with the movable track or conveyer 24. A double acting winch 22 is also provided at the front end of the forward car 15 so 10 that the cable can be wound forward or back as desired. I have not shown the means for supporting the cable at the front end of the section to be laid or on the rear end of the construction train, because this 15 arrangement will be well understood, and I am showing simply enough to illustrate how my improved method can be carried out.

Assuming that the trucks with the movable track 25 which is laid thereon, has been 20 pushed out to the desired distance. The trucks 17 are then propelled forward in a long train covering the entire distance of track to be laid. The ties 18 on the trucks are then dumped, and the trucks are arranged 25 so that there will be the appropriate number of ties for each section between the ties 14 already laid. The empty trucks 17 are then drawn back to the construction train, and the crew at once proceed to lay 30 the ties 18, tamp them, and grade them properly for a permanent track. This can be assisted by means of the ordinary leveling board 18^a, or by any usual appliance. As soon as the train of trucks 17 is withdrawn, the cable carries forward the trucks 26 which are arranged on flat cars behind the truck 17, and these trucks carry the permanent rails 27, and the trucks 26 are propelled forward to the same extent that the 35 trucks 17 have previously covered, and by the time the rails 27 are carried forward as stated, the crew will have laid the ties 18 permanently, so that the rails can then be unloaded and spiked down permanently on 40 the previously laid ties.

It will be noticed that in this way the crew are not interfering with each other, and that the work can be carried forward to the best possible advantage. If desired 50 still other cars may be arranged behind the flat cars 15 carrying the rails 27, and these may be loaded with ballast and the ballast can be carried forward in the way already indicated, after the permanent rails have 55 been laid, and the track can be ballasted.

Thus it will be seen that I can lay a very long section of permanent track and have every man in the crew working to good advantage. After the section of track has 60 been laid as stated, the trucks are hauled back on the flat cars, the construction train pulled back out of the way, and a new train advanced along the just laid permanent track and the operation repeated.

65 To facilitate the work the rails 27 can

be bolted together on the flat cars, and where the work is carried forward on viaducts, elevated structures, or the like, the track 11 can be extended a long distance in front of the construction train, the rails 70 carried out on the conveying means shown, or similar means, for the necessary distance say a quarter of a mile or more, and the rails then laid on the prepared bed.

I have shown apparatus well intended to 75 carry out the method described, but in this application I do not lay claim to the apparatus, and on the other hand I do not limit myself to the use of any particular form of apparatus.

80 I claim:—

1. The improvement in the art of railroad building, which consists in first laying to grade a series of ties which are spaced apart in multiples of the space of the full number of ties to be laid, next laying a temporary track on the aforesaid spaced ties, next running out a portable track on the said temporary track, next conveying ties on said portable track and dumping the required 90 number of ties between the previously laid spaced ties, next conveying the track rails along the portable track, and depositing and laying them upon the previously laid ties.

95 2. The improvement in the art of building railroad tracks, which consists in first laying to grade a series of ties which are spaced apart at greater distances than the ordinary track ties, laying a temporary track 100 on the said spaced ties, conveying the necessary number of ties along the temporary track and dumping these in required number in the spaces between the previously laid ties, next permanently laying the ties 105 dumped as aforesaid, next conveying the necessary rails over the temporary track and depositing them at required distances along the laid ties, and finally laying the rails.

110 3. The improvement in the art of building railroads, which consists in first laying out on the roadbed and spacing apart a series of ties which are spaced at greater distances than the ordinary track ties, then laying a temporary track upon said spaced ties, 115 providing at the beginning of the track to be laid a construction train having trucks loaded with ties and rails thereon, next propelling the trucks forward over the temporary track and depositing the necessary number of ties between the previously spaced ties, next laying the ties just dumped and withdrawing the tie trucks, and finally propelling the rail trucks over the temporary track and laying the rails in position for the 120 permanent track.

125 4. The improvement in the art of building railroads which consists in permanently laying along the roadbed in advance of the permanent track a series of ties which are 130

- spaced apart at greater distances than the ordinary track ties, laying a temporary track upon the said spaced ties, running out a portable track on trucks upon the said temporary track, propelling forward on said portable track a series of trucks loaded with the necessary number of ties to lay the permanent track, next permanently placing these ties between the previously spaced ties, 5 next withdrawing the trucks, next propelling trucks loaded with rails over the portable track, and finally unloading and laying the permanent rails.
5. The improvement in the art of building railroads which consists in providing a train of flat cars with tracks carrying portable trucks loaded with ties and portable trucks loaded with rails, the latter being arranged behind the tie trucks, laying a temporary track along the roadbed in advance of the flat cars, then propelling the tie trucks from the flat cars over said temporary track, dumping the ties from said trucks and laying them permanently on the 20 roadbed, then withdrawing the tie trucks and advancing the rail trucks over said temporary track, and finally depositing the rails from said rail trucks and laying the permanent track on the previously laid ties.
- 30 6. The improvement in the art of building railroads which consists in providing upon a train of flat cars parallel tracks on which are arranged in order first a series of trucks loaded with ties, next a series of 35 trucks loaded with rails, next a series of trucks loaded with ballast, then laying a temporary track along the roadbed in advance of the train of flat cars, then propelling the tie trucks from the flat cars along 40 said temporary track, then unloading the said trucks and laying the ties for a permanent track, then withdrawing the tie trucks and advancing the rail trucks on said temporary track, next laying the rails on the 45 aforesaid ties, then withdrawing the rail trucks, and advancing the ballast trucks and depositing the ballast upon the track.
7. The improvement in the art of building railroads, which consists in laying an extensible track along the roadbed, next conveying along said extensible track a sufficient number of ties for the permanent track, next laying said ties for the permanent track, 50 then conveying the permanent track rails along said extensible track, and finally laying said permanent rails.
8. The improvement in the art of building railroads, which consists in extending a temporary track along the roadbed, then running an extensible track along said temporary track, then conveying on said extensible track a sufficient number of ties for the permanent track, then laying said ties for the permanent track, then conveying along said extensible track a sufficient number of rails for the permanent track, and finally laying said permanent rails.
9. The improvement in the art of building railroads, which consists in first placing at necessary intervals along the roadbed engineers' stakes indicating the line and grade of the track to be laid, next extending conveying means along the roadbed, next conveying the ties on said conveying means and depositing them at necessary intervals along 70 the roadbed, next laying the ties to the permanent line and grade indicated by the engineers' stakes, and finally laying the rails 75 permanently on said ties.
10. The improvement in the art of building railroads which consists in placing at intervals along the roadbed stakes indicating the line and grade of track to be laid, then laying a temporary track along the roadbed, next conveying the ties along said temporary track, depositing them at necessary 80 intervals, and laying the ties to the grade and line of the permanent track, then conveying along said temporary track the necessary rails to cover the previously laid ties, 85 and finally permanently laying the rails on said ties.
11. The improvement in the art of building railroads on a previously prepared roadbed, which consists in arranging the track 90 materials on a construction train, extending a temporary track out over the roadbed for the distance of a plurality of cars in advance of the construction train, conveying the track material out over this temporary 95 track, and then depositing and laying the permanent track.
